United States Patent Office

Des. 221,230
Patented July 20, 1971

221,230

MICROPHONE STAND

Robert L. Deschamps, West Chicago, Ill., assignor to
Shure Brothers Incorporated

Filed Nov. 3, 1969, Ser. No. 19,886

Term of patent 14 years

Int. Cl. D14—01

U.S. Cl. D26—14

FIG. 1 is a perspective view of a microphone stand embodying my new design;

FIG. 2 is a side elevation view of the microphone stand of FIG. 1;

FIG. 3 is a front elevation view of the microphone stand of FIG. 1;

FIG. 4 is a top view of the microphone stand of FIG. 1; and

FIG. 5 is a rear elevation view of the microphone stand of FIG. 1.

The microphone is shown in broken lines for illustrative purposes only and forms no part of the claim.

I claim:

The ornamental design for a microphone stand, as shown and described.
